UNITED STATES PATENT OFFICE.

JOSEPH FRANK, OF NEW YORK, N. Y.

BATTEN FOR NARROW-WARE LOOMS.

980,236.

Specification of Letters Patent.

Patented Jan. 3, 1911.

Application filed September 21, 1910. Serial No. 583,017.

To all whom it may concern:

Be it known that I, JOSEPH FRANK, a citizen of the United States, residing in New York city, county of New York, and State of New York, have invented certain new and useful Improvements in Battens for Narrow-Ware Looms; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to increase the capacity of battens for weaving narrow-ware goods in which the shuttles move in curved races crossing each other between the weaving spaces. This object I accomplish by arranging the shuttles in two series in which those of one series alternate with and overlap those of the other series and stand in a vertical plane which is relatively in advance of the latter.

In the accompanying drawings, Figure 1 is a front elevation of a section of the improved batten-structure, partly in section; Fig. 2 is a vertical sectional view taken 20 through the space between two adjoining shuttle blocks; the shuttles appearing in broken outline to prevent confusion; Fig. 3 is a horizontal sectional view through the shuttle blocks in about the plane of the races, 30 the shuttles appearing in plan; Fig. 4 is an enlarged detail view of one of the shuttle-blocks as it appears in Fig. 3, the pinions therein appearing in elevation; and, Figs. 5 and 6 are cross-sectional views of the 35 shuttles.

In the batten-proper *a* is arranged in the usual manner the reciprocating rack *b* having the toothed strip *c* forming the toothed portion thereof; carried by the batten proper and secured thereto by the usual means comprising, say, the uprights *d* and connecting strip *e*, are the spaced shuttle blocks *f*.

In the blocks are formed grooves arranged 50 in two series, each groove of one series being intersected by two grooves of the other series and such intersections occurring at the middle points of the blocks. The grooves marked *g* are shallower than the grooves marked *g'*, the backs of the former being indicated at *h* and of the latter at *h'*.

The grooves *g* each have at the top the rib *i*; their bottom surfaces are flat except for a rabbet *i'*. The grooves *g'* have each at the top the rib *j*; their bottom surfaces 60 are likewise flat, except for the rabbet *j'*.

The shuttles *k* and *k'* are formed to fit the grooves *g* and *g'*, respectively, each shuttle *k* having a channel *l* at the top and a flange *m* at the under side thereof engaging, 65 respectively, with the rib *i* and rabbet *i'* of the corresponding groove *g*, and each shuttle *k'* having a channel *n* at the top and a flange *o* at the under side thereof engaging, respectively, with the rib *j* and rabbet *j'* 70 of the corresponding groove *g'*. In addition, each shuttle *k* has, relatively back of its flange and in its under side, a rack *p* and each shuttle *k'* has in its under side a groove *q* (in the same vertical plane as the 75 racks *p* of the shuttles *k*) and, back of said groove, a rack *r*.

Directly beneath the intersection of the grooves in each block, and housed in the block, a pair of pinions *s* and *s'* is journaled, 80 their journal being afforded by the screw or the like *t* and their teeth projecting into the grooves where the latter intersect; they mesh with the rack *b* and are respectively arranged in the same vertical planes as the 85 racks *p* and *r* of the shuttles *k* and *k'*, respectively.

When each shuttle is in the mid-position of its race it is engaged simultaneously with two pinions *s* and *s'* (or *s'* and *s*) and upon 90 the rack being reciprocated the shuttles will oscillate back and forth in said races.

In view of the construction herein described, since the series of shuttles *k* stand in advance of (that is, relatively nearer the 95 front of batten-proper *a* than) the series of shuttles *k'* and since the shuttles *k* overlap the shuttles *k'* when the several shuttles are in their mid-positions in their races, a saving of space is accomplished which is 100 equal to the amount of overlapping allowed each two shuttles multiplied by the number of weaving units which the batten structure is made to include.

Having thus fully described my invention, 105 what I claim as new and desire to secure by Letters Patent is:

1. The combination of the batten proper, a structure carried thereby and forming a series of weaving spaces, said structure having two series of curved races arranged one 110 nearer the front of the batten proper than

- the other, the races of one series intersecting those of the other series at points between the spaces, two series of curved shuttles arranged respectively in said series of grooves, one series of shuttles in advance of the other, and means for reciprocating the shuttles, the shuttles of one series overlapping those of the other series when the shuttles are in their mid-positions in the races, substantially as described.
- 10 2. The combination of the batten proper, a structure carried thereby and forming a series of weaving spaces, said structure having two series of curved grooves forming races, the grooves of one series intersecting 15 those of the other series at points between

the spaces, two series of curved shuttles arranged respectively in said series of grooves, one series of shuttles in advance of the other, and means for reciprocating the shuttles, the shuttles of one series overlapping those of the other series when the shuttles are in their mid-positions in the grooves, substantially as described.

In testimony that I claim the foregoing I have hereunto set my hand this 9th day 25 of September, 1910.

JOSEPH FRANK.
